TOOTHBRUSH HOLDER

Ebold J. Hagglund, Erie, Pa.

Application March 17, 1945, Serial No. 583,365

5 Claims. (Cl. 206—15.1)

1

This invention relates to sanitary containers, and more particularly to containers designed to receive tooth brushes.

It is a purpose and one of the objects of the invention to provide a closed container in which several tooth brushes may be placed and removed at will. The invention is also directed to the provision of a container of such structure that brushes are protected against dirt, dust, and moisture and, if placed therein in a wet condition, will dry out as readily as they would outside of the container.

It is also an object of the invention to provide a container that not only accommodates several tooth brushes, but requires that these brushes be sufficiently separated, one from another, to satisfy sanitary requirements.

Additionally, it is an object of the invention to provide a container that is constructed of relatively few simple and easily assembled parts, the simplicity and ease of assembly of the parts greatly facilitating disassembly from time to time for cleaning purposes. And it is also an object of the invention to provide an attractive container for tooth brushes that is easily mounted in a convenient position of use and will contain, in addition to the tooth brushes, a tube or jar of cleansing substance.

Other objects and advantages of the invention will be more fully understood from a consideration of the following specification, taken in conjunction with the accompanying drawing; and in which

Fig. 1 is a front elevational view of a tooth brush container embodying one form of the invention, parts being broken away to more clearly disclose certain of the structural details;

Fig. 2 is an end elevational view of the structure shown in Fig. 1;

Fig. 3 is a top plan view of the structure shown in Fig. 1, parts being broken away to disclose the tooth brush mounting structure;

Fig. 4 is a vertical sectional view, taken substantially on the line 4—4 of Fig. 3 and shows the bottom closure of the container in opened position and a tooth brush being mounted in the container;

Fig. 5 is an enlarged detailed vertical sectional view taken substantially as indicated by the line 5—5 of Fig. 3 and shows the mounting and spring position of a shutter located in the container;

Fig. 6 is a fragmentary vertical sectional view taken substantially on the line 6—6 of Fig. 5;

Fig. 7 is a fragmentary vertical sectional view taken on the line 7—7 of Fig. 5;

2

Fig. 8 is a fragmentary vertical sectional view of the closure hinge structure; and

Fig. 9 is similar to Fig. 8 and shows the method of mounting the hinge closure on the container.

Referring more particularly to the drawing, the reference numeral 10 is employed to generally designate a closed container for tooth brushes in which is embodied one form of the invention. The container includes a body portion 11, top 12, and bottom closure 13. The body portion 11 is shown to be rectangular and consists of front and rear walls 14 and 15, and end walls 16 and 17. These walls may meet in a sharp angle or, for purposes of appearance, may be rounded, substantially as suggested in the drawing. Adjacent the upper edges of the walls of the body portion is a horizontally disposed ledge or shelf 18. This ledge extends entirely around the walls of the container and forms an interior, central, rectangular opening 19. A suitable number of open-ended slots 21 are formed in opposite edges of the ledge; namely, the portions extending from the front and rear walls 14 and 15. The slots 21, as will be hereinafter more fully set forth, cooperate with other structural parts in the mounting of tooth brushes in the container.

Mounted in the opening 19 is a shutter 22. This shutter is proportioned to substantially fill the opening without contacting any of the edges of

the ledge 18. Referring particularly to Figs. 3 and 5, it will be noted that a stub shaft 23 of the shutter projects into a semicircular boss 24 formed in that portion of the ledge 18 adjacent end wall 16. The boss provides a downwardly

opening recess in which to locate this shaft, and integral or attached flanges 26 may form a continuation of the downwardly opening recess to provide space in which to mount a locking member 27. This member may be of spring metal and contoured as shown in Fig. 6, and is compressible

to snap into engagement with the flanges 26 for the purpose of bringing the portion 28 thereof into contact with the undersurface of the shaft 23. A bearing of this nature for the shaft is well adapted to use in materials that might have a tendency to become distorted as a result of being used in the presence of heat and moisture, as is commonly found in a lavatory or bathroom.

The other end of the shutter 22 mounts a disk

29, from the center of which projects a bearing shaft 31. That portion of the ledge 18, adjacent the end wall 17, includes a circular element 32, having a rim 33 of a diameter corresponding to the diameter of the disk 29. The shaft 31, when

the shutter is mounted for use, projects through

and beyond the recess 34 of the element 32 into a bearing recess 36. A loosely coiled spring 37 is mounted in the recess 34, one end of the spring being permanently attached to the shaft 31 and the other end permanently engaged with the rim 33. The spring 37 is so designed that when mounted in the manner described, the shutter 22 will be yieldingly held in the plane of the ledge 18, thus closing the opening 19. However, this spring 37, or its equivalent, permits oscillation of the shutter about its pivot shafts 23 and 31 to an extent to permit entry of the bristle end of a tooth brush through the opening 19.

The top 12, of course, is of substantially the same contour as the body portion 11 and includes front and side walls that are, in considering the container as a whole, substantial continuations of the body portion walls 14, 15, 16, and 17. A top wall 38 serves to enclose the shutter structure and tooth brushes when the top 12 is engaged with the body portion 11. For convenience, it is found desirable to form at least a part of the walls of the top of transparent material in order that the various owners of tooth brushes may observe and be enabled to remove their own tooth brushes. In the rear wall of the top—namely, that corresponding to the rear wall 15 of the body portion—a number of apertures 39 are provided. Any suitable means may be utilized by which to locate and retain the top 12 on the body portion, such, for example, as through the provision of an interior rim 41 which may form the outer edge of the ledge 18.

The bottom closure 13 is hinged along one edge to the lower edge of the rear wall 15. Since it is desirable that the parts of a container of this nature be readily separable to facilitate maintenance in a cleanly and sanitary condition, the closure 13 is made removable. The hinge structure shown includes a pair of circular lugs 42, carried by the rear edge of the closure, and from which pivot pins 43 project in opposite directions. On the outer face of the wall 15, suitable lugs 44 are provided, in each of which is an upwardly opening slot 46 of a size adapted to receive pin 43. The closure 13 may be assembled with the body portion 11 in the manner illustrated in Figs. 9 and 8. For purposes of providing proper fit of the closure 13 with the body portion, said closure may include an annular rim 47 which, with the closure in the position shown in Fig. 8, lies within the body portion of the container. The inner face of the closure may also be fitted with a shelf 48 on which to locate a tube or small jar of cleansing material, indicated at 49. A small guard plate 50 may also be provided by which to prevent displacement of the tube 49 when the closure 13 is moved into engagement with the body portion 11. Although no specific fastener is shown, it will be understood that a suitable latch is provided by which to secure the closure 13 in closed position.

To more clearly understand the advantages of the invention as heretofore set out, a description of its use is provided. It can be assumed that the container 10 is removably attached to a vertical wall by any well known means, such, for example, as the structure suggested in Fig. 3 of the drawing. Herein a keystone shaped member 51, extending rearwardly of the container, is adapted to project into a wall attached bracket 52, edges of the bracket and member interfitting in the well known manner illustrated. The top 12 has, of course, been placed on the body portion 11 to provide an enclosed space above the

shutter 22. The closure 13 is swung into its open position (see Fig. 4) and the tooth-paste tube or like container, may be mounted on the shelf 48. A tooth brush may be projected upwardly into the body portion 11 through the opening provided by the opened position of the closure 13. The bristle end of the tooth brush contacts the shutter 22, rotating it substantially as suggested in Fig. 4, enabling movement of the bristle end into the space above the shutter. The narrow portion of the brush, below the bristles, may now move into one of the slots 21, with the bristles turned forwardly of the container. The spring 37 will cause the shutter to move back into the plane of the ledge 18. It will be understood that the shutter does not serve to support the tooth brush but merely holds it in position within its slot 21. Thus, additional tooth brushes may be placed in the container and supported in other of the slots 21, each brush, when inserted, causing the shutter to rotate as already described. When it is desired to remove one of the brushes, the brush is moved laterally into contact with the edge of the shutter and thence upwardly, thus causing the shutter to rotate to nearly a vertical position and allowing removal of the brush. Suitable apertures 53 are provided adjacent the lower edge of the rear wall 15 and these openings, together with the openings 39 on the top, make possible circulation of air in the container. As already pointed out, the shutter 22 does not have a tight fit in the opening 19 and, thus, air may enter either the top or bottom openings and circulate through the container.

Although applicant has shown and described only one modification of his invention, it will be apparent to those skilled in the art that the more specific structural details shown may be modified as required and that such modifications are contemplated as being within the spirit and scope of the invention as set out in the annexed claims.

Having thus set forth my invention, what I claim as new and for which I desire protection by Letters Patent is:

1. A tooth brush holder comprising a container having a closed top and an open bottom, a continuous ledge extending inwardly of the walls of said container, said ledge serving to divide the interior of said container into two compartments and providing a restricted opening therebetween, at least a portion of said ledge having slots joining said opening, a shutter mounted within the limits of said opening, and pivotal means operable to yieldingly maintain said shutter in a position to close said opening.

2. A tooth brush holder comprising a container having a closed top and an open bottom, a continuous ledge extending inwardly of the walls of said container at a point intermediate said top and bottom, said ledge serving to divide said container into upper and lower compartments and providing a restricted opening therebetween, a shutter pivotally mounted to operate within the limits of said opening and adapted, when in the plane of said ledge, to close said opening, and means operable to yieldingly maintain said shutter in the plane of said ledge whereby to normally close off the upper compartment.

3. A tooth brush holder comprising a container having a closed top and an open bottom, a continuous ledge extending inwardly of the walls of said container at a point intermediate said top and bottom, said ledge serving to divide said container into upper and lower compartments

ments and providing a restricted opening therebetween, at least a portion of said ledge having slots joining said opening, said slots being of a size to receive the handle portion of a brush, a shutter in said opening in the plane of said ledge, said shutter serving to close said slots, and means mounting said shutter for pivotal movement out of the plane of said ledge whereby to facilitate mounting and removal of a brush in any one of said slots.

4. A tooth brush holder comprising a container formed by separable upper and lower parts, the upper part constituting a closure for the top opening of the lower part, a brush supporting ledge extending inwardly of the upright walls of said lower part and providing a restricted connecting opening between the interiors of said upper and lower parts, a shutter in said opening, means mounting said shutter for oscillation into and out of the plane of said ledge, and a bottom closure for the lower part of said container, said closure being pivotally movable into an open position to give access to the interior of said container and the mounting and removal of a brush.

5. A tooth brush holder comprising a container formed by separable upper and lower parts, the upper part constituting a closure for the top opening of the lower part, a continuous ledge extending inwardly of the walls of said container, said ledge serving to divide the interior of said container into two compartments and providing

a restricted opening therebetween, said ledge having slots on opposite sides of and joining said restricted opening, a shutter pivotally mounted in said opening in a manner to be oscillatable into and out of the plane of said ledge whereby to open or close the open ends of said slots, and a closure for the bottom opening of the lower part of said container, said closure being pivotally swingable into a position to give access to the interior of the lower part of said container and the mounting and removal of a brush with respect to said ledge and shutter.
